US0D1093243S

(12) **United States Design Patent** (10) Patent No.: **US D1,093,243 S**
 Yamashita et al. (45) Date of Patent: ** Sep. 16, 2025

(54) **HOOD FOR MOTOR VEHICLE**

(71) Applicant: **Dr. Ing. h.c. F. Porsche Aktiengesellschaft**, Stuttgart (DE)

(72) Inventors: **Shuichi Yamashita**, Stuttgart (DE); **Woosung Chung**, Stuttgart (DE)

(73) Assignee: **Dr. Ing. h.c. F. Porsche Aktiengesellschaft** (DE)

(**) Term: **15 Years**

(21) Appl. No.: **29/915,669**

(22) Filed: **Nov. 2, 2023**

(30) **Foreign Application Priority Data**

Jun. 5, 2023 (EM) 015023618-0021

(51) **LOC (15) Cl.** **12-08**

(52) **U.S. Cl.**

USPC **D12/173**

(58) **Field of Classification Search**

USPC D12/173, 86, 90, 91, 164, 169; D21/424, D21/433, 495, 533

CPC B60R 13/04; B62D 25/10; B62D 25/08; B62D 25/085
